[57] ABSTRACT

Compounds of the formula

wherein n is 1 or 2, X is F, NO₂, H or CH₃, R₁ is H or CH₃ and R₂ is H or lower alkyl of 1-4 carbon atoms which can be polymerized to produce high-energy binders used in explosive compositions are prepared by reacting an amine of the formula

with

when n is 1 and with

and trifluoroacetic anhydride in the presence of p-toluenesulfonic acid when n is 2.

NITRO SUBSTITUTED ACRYLIC ACID AMIDES

BACKGROUND OF THE INVENTION

This invention relates generally to explosive compounds and more particularly to carboxylic acid amides which can be polymerized for binders useful in explosive compositions and to a method of preparation thereof.

For an explosive binder to be considered good it must not only be stable and compatible with the other components of the explosive composition but must also be sufficiently energetic to release energy when the composition is detonated. The latter is desirable so that the explosive composition when detonated will release as much energy as possible per unit weight. Thus a continuing search has long existed for highly energetic explosive binders and for monomers which are the precursors for these binders.

SUMMARY OF THE INVENTION

Accordingly one object of this invention is to provide new organic compounds.

Another object of this invention is to provide organic compounds which can be polymerized into highly energetic binders for explosive compositions.

A still further object of this invention is to provide a method for the preparation of organic compounds which can be polymerized into highly energetic binders for explosive compositions.

These and other objects of this invention are accomplished by providing compounds of the formula

wherein n is 1 or 2, X is F, NO₂, H or CH₃, R₁ is H or CH₃ and R₂ is H or lower alkyl of 1-4 carbon atoms which are prepared by contacting

with

when n is 1 and with

and trifluoroacetic anhydride in the presence of p-toluenesulfonic acid when n is 2.

DESCRIPTION OF THE PREFERRED EMBODIMENTS

The carboxylic acid amides of this invention are prepared in two alternative ways depending on the value

of n in formula (I). When n is 1 the amides are prepared by contacting in solution an acid chloride of the formula

with an amine of the formula

preferably in the presence of an esterification catalyst such as pyridine at a temperature between about 0°C and room temperature but preferably between 0°C and 10°C.

Compounds of formula (I) wherein n is 2 are prepared by contacting in solution an acid of the formula

and trifluoroacetic anhydride with an amine of the formula

preferably in the presence of a catalyst such as p-toluenesulfonic acid at about room temperature.

The general nature of the invention having been set forth, the following examples are presented as specific illustrations thereof. It will be understood that the invention is not limited to these specific examples but is susceptible to various modifications that will be recognized by one of ordinary skill in the art.

EXAMPLE 1

N - (2-fluoro-2,2-dinitroethyl) acrylamide

To a solution of 11.6g of 2-fluoro-2,2-dinitroethylamine the preparation of which is disclosed in Application Ser. No. 849,277 filed Aug. 5, 1969, now abandoned, entitled Chemical and Method of Preparation Thereof by Horst G. Adolph and Richard R. Minesinger, in 50 ml of methylene chloride and 7.3 ml of pyridine, containing a little hydroquinone, was added 7.3 ml of acryloyl chloride, dropwise, at ice-bath temperature. After standing overnight at 10°C the solution was washed with dilute sulfuric acid, dried with anhydrous magnesium sulfate, and filtered. After evaporation of the solvent, the residual oil was crystallized from methylene chloride to give 2.43g of the desired product, mp 73°-74.5°C whose IR and NMR were consistent with the desired structure.

EXAMPLE 2

N,N-Bis(2-fluoro-2,2-dinitroethyl) acrylamide

To a slurry of 1.0g (3.46 mole) of bis(2-fluoro-2,2-dinitroethyl) amine, the preparation of which is disclosed in application Ser. No. 849,277 filed Aug. 5, 1969 entitled Chemical and Method of Preparation Thereof by Horst G. Adolph and Richard R. Minesinger, in 3 ml of trifluoroacetic anhydride was added 1.5 ml of acrylic acid and 0.1g of p-tolene sulfonic acid monohydrate with stirring. After 15 minutes the

bis-amine had completely dissolved and the solution was allowed to stand at ambient temperature for 5 days. The solution was then taken up in 50 ml of methylene chloride and washed consecutively with 2-50 ml portions of water, 1-50 ml portion of saturated aqueous sodium bicarbonate and 1-50 ml portion of water. After drying with anhydrous magnesium sulfate and filtering, the solvent was removed on a rotavap to give an oil which spontaneously crystallized. Upon recrystallization from methylene chloride, 0.82g (69 percent yield) of the desired compound was obtained, m.p. 111°-113°C.

The other compounds of formula I can be prepared in the same manner except that one would substitute the appropriate starting materials.

Numerous modifications and variations of the present invention are possible in light of the above teachings. It is therefore to be understood that within the scope of the appended claims the invention may be practiced otherwise than as specifically described herein.

What is claimed as new and desired to be secured by Letters Patent of the United States is:

1. A compound of the formula

wherein n is an integer from 1 to 2 inclusive, X is selected from the group consisting of F, NO₂, H and CH₃, R₁ is selected from the group consisting of H and CH₃ and R₂ is selected from the group consisting of H and lower alkyl of 1-4 carbon atoms.

2. A compound according to claim 1 wherein X is F.

3. A compound of claim 2 wherein R₁ and R₂ are both H.

4. A compound according to claim 3 which is N-(2-fluoro-2,2-dinitroethyl)acrylamide.

5. A compound according to claim 3 which is N,N-bis(2-fluoro-2,2-dinitroethyl) acrylamide.

6. A method of preparing the compounds of claim 1 wherein n is 1 comprising contacting in solution an amine of the formula

with an acid chloride of the formula

in the presence of an esterification catalyst at a temperature between 0°C and room temperature.

7. A method of preparing the compounds of claim 1 wherein n is 2 comprising contacting in solution an acid of the formula

and trifluoroacetic anhydride with an amine of formula

in the presence of an amidation catalyst at about room temperature.

8. A method of preparing the compounds of claim 1 wherein n is 1 comprising contacting in solution an amine of the formula

with an acid chloride of the formula

at a temperature between 0°C and room temperature.

9. A method of preparing the compounds of claim 1 wherein n is 2 comprising contacting in solution an acid of the formula

and trifluoroacetic anhydride with an amine of formula

at about room temperature.
